GUN

Charles F. Lefever, Plymouth, Mich., assignor to
 Daisy Manufacturing Company, Plymouth,
 Mich., a corporation of Michigan

Original application September 12, 1932, Serial
 No. 632,856. Divided and this application
 February 20, 1933, Serial No. 657,720

4 Claims. (Cl. 124—10)

The invention relates to guns and forms a divisional of my pending application for patent Serial No. 632,856, filed September 12, 1932. The present application relates more particularly to the construction of the removable shooting barrel and further to the means for locking said shooting barrel in position and for simultaneously controlling the closure for the shot opening in a magazine barrel and various other features as hereinafter set forth.

In the drawing:

Fig. 1 is a side elevation of the gun;

Fig. 2 is a longitudinal section through the shooting barrel and magazine;

Fig. 3 is a cross section on line 3—3 of Fig. 2;

Fig. 4 is an end elevation of the false barrel with the true barrel removed.

Figs. 5 and 5A are perspective views showing the interlocking portions respectively of the false barrel and shooting barrel.

As shown, A is the stock, B the false barrel, C the frame, D the pivoted lever for use in compressing the spring which actuates the air plunger. As the specific construction of spring pressed plunger and actuating mechanism therefor forms no part of the present invention, I deem it unnecessary to further describe or illustrate the same.

Heretofore guns have been provided with detachable shooting barrels such as E which are detachably positioned within the false barrel B while the space within the latter barrel surrounding the shooting barrel is utilized for forming a magazine or shot reservoir. The present construction includes this feature but I have devised a novel means of locking the shooting barrel in position which also cooperates to form a closure for the feed opening into the magazine. As shown, the barrel E is provided at its rear end with a tapered portion F which fits within the abutment G for the plunger (not shown). A guide H surrounds the barrel E adjacent to the abutment and serves to direct the shot into a channel I from which they pass successively through an aperture J into the barrel E. At the forward end of the barrel E is a cap member K which is formed of a cupped sheet metal blank having its body portion L drawn inward to a smaller diameter leaving a return bent flange M. The center of the cap is provided with an inwardly extending flange N which fits about the shooting barrel E and is attached thereto. The body portion L has a cut away portion O for registration with a shot feed aperture P in the false barrel in one

position of rotative adjustment. This body portion also has struck out therefrom a lug Q which serves as a guide for inserting the cap in the false barrel and also as a lock for retaining it in position. Cooperating with the cap member O and lug Q thereof is a reinforcement member fitting within the false barrel B and this member is formed as a part of a sight member R. Thus as shown, the sight member R is formed as an upwardly projecting flange on a cylindrical member S which extends part way around within the false barrel B, leaving a gap which forms an entrance channel T for the lug Q. The portion S is also cut away at U to permit the turning of the cap K after the lug Q has passed through the channel T, and the edges V and W of this cut away portion form shoulders for respectively holding the cap against longitudinal or further rotative movement.

With the construction just described, when the barrel E is inserted within the false barrel B, its inner end F will engage the aperture in the abutment G and the lug Q on the cap O will enter the channel T. The cap and barrel are moved inward until the lug Q passes beyond the shoulder V, after which the cap may be adjusted rotatively. This forms in effect a bayonet lock which holds the shooting barrel from accidental displacement. It also serves the function of a valve or closure for the shot feed aperture P as in one position of rotative adjustment the cut away portion O is in registration with this aperture to permit of introduction of shot, while in the locked position the aperture P is closed by an imperforate portion of the body L.

What I claim as my invention is:

1. In a gun, the combination with a false barrel provided with a piston abutment therein, of a true barrel insertable through the muzzle of said false barrel having its inner end slidably engaging the socket in said piston abutment, a cap mounted at the outer end of said true barrel provided with a cylindrical flange telescopically engaging said false barrel, said flange being provided with a struck-out portion at one point in its circumference, a reinforcement for the muzzle end of said false barrel arranged within the same and cut away to form a channel for the passage of said struck out portion on said cap, said reinforcement also cooperating with said struck-out portion to form a bayonet lock for retaining said true barrel within said false barrel.

2. In a gun, the combination with a false bar-

- rel provided with a piston abutment therein, a reinforcement member for the muzzle end of said false barrel in the form of a bushing fitting therein and having an upwardly extending flange extending through a slit in said false barrel and forming a bead sight, said bushing being cut away at one point to form a channel longitudinally therethrough and being apertured at another point in registration with a shot entrance aperture in said false barrel, a true barrel insertable through the muzzle of said false barrel having its inner end slidably engaging a socket in said piston abutment, a cap secured to the outer end of said true barrel provided with a cylindrical flange telescopically engaging said reinforcement bushing, said flange being apertured at one point for registration with said shot entrance aperture, and a struck out portion on another part of said cylindrical flange adapted to enter through the channel in said bushing and cooperating with the latter to form a bayonet lock.
5. In a gun, the combination with a false barrel provided with a piston abutment therein, of a true barrel insertable through the muzzle of said false barrel having its inner end slidably engaging the socket in said abutment, a cap mounted on the outer end of said true barrel provided with a cylindrical flange telescopically engaging said false barrel, said flange being
- provided with a struck-out portion at one point in its circumference, and a reinforcement for the muzzle end of said false barrel arranged within the same and cut away to form a channel for the passage of said struck-out portion on said cap, and further cut away to permit a limited rotation of said cap and to form shoulders for holding the cap against longitudinal or further rotative movement, thereby producing in effect a bayonet lock.
4. In a gun, the combination with a false barrel provided with a piston abutment therein, a re-enforcing member for the muzzle end of the false barrel in the form of a bushing fitting therein and having an upwardly projecting flange extending through a slit in said false barrel and forming a bead sight, said bushing being cut away at one point to form a channel longitudinally therethrough, a true barrel insertable through the muzzle of said false barrel having its inner end slidably engaging a socket in said piston abutment, a cap secured to the outer end of said true barrel provided with a cylindrical flange telescopically engaging said reinforcement bushing and a struck-out portion on said cylindrical flange adapted to enter through the channel in said bushing and cooperate with the latter to form a bayonet lock.
3. In a gun, the combination with a false barrel provided with a piston abutment therein, of a true barrel insertable through the muzzle of said false barrel having its inner end slidably engaging the socket in said abutment, a cap mounted on the outer end of said true barrel provided with a cylindrical flange telescopically engaging said reinforcement bushing, said flange being
